DESIGN FOR TRIMMING.

SPECIFICATION forming part of Design No. 31,332, dated August 1, 1899.

Application filed July 1, 1899. Serial No. 722,609. Term of patent 3½ years.

To all whom it may concern:

Be it known that I, MAURICE GREENBERG, a subject of the Czar of Russia, residing in the city and county of Philadelphia, State of Pennsylvania, have invented and produced a new and original Design for Trimming, of which the following is a specification, reference being had to the accompanying drawings, forming part thereof.

10 The leading feature of my design for a trimming is a facing of loops and bars appearing through the same.

Figure 1 represents a face view of a piece of trimming embodying my design. Fig. 2 15 represents a section thereof on line xx , Fig. 1.

In the drawings, A designates a piece of trimming having a facing composed of loops B, and bars C on the back thereof appearing through the same.

Having thus described my invention, what I claim as new, and desire to secure by Letters Patent, is—

The design for a trimming substantially as shown and described.

MAURICE GREENBERG.
